(57) **CLAIM**

The ornamental design for a scrubbing and massaging foot device, as shown and described.

DESCRIPTION

FIG. 1 is a front perspective view of the scrubbing and massaging foot device of the present invention showing my new design;

FIG. 2 is a front side elevational view thereof;

FIG. 3 is a back side elevational view thereof;

FIG. 4 is a side elevational view thereof;

FIG. 5 is another side elevational view thereof;

FIG. 6 is a top plan view thereof; and,

FIG. 7 is a bottom plan view thereof.

The broken lines that are immediately adjacent the surface shading represent the boundaries of the claim while all of the other broken lines illustrate portions of the device, none of which form no part of the claimed design.
